United States Patent Office

Des. 186,770
Patented Dec. 1, 1959

186,770

SOUND TRANSDUCING APPARATUS

Leo J. Aucoin, West Hartford, and Frank L. Moore,
Newington, Conn., assignors to The Gray Manufac-
turing Company, a corporation of Connecticut

Application October 22, 1958, Serial No. 53,083

Term of patent 14 years

(Cl. D26—14)

Fig. 1.

Fig. 2.

Fig. 1 is a perspective view showing the front, top, and one end of a sound transducing apparatus, showing our new design; and

Fig. 2 is a perspective view showing the rear, top, and the other end thereof.

We claim:

The ornamental design for a sound transducing apparatus, as shown.
